UNITED STATES PATENT OFFICE.

LESTER S. GUNDERMAN, OF PITTSBURGH, PENNSYLVANIA.

SAFETY DEVICE FOR CLOTHES WRINGERS.

Application filed November 16, 1922. Serial No. 601,253.

To all whom it may concern:

Be it known that I, LESTER S. GUNDERMAN, a citizen of the United States, residing at Pittsburgh, county of Allegheny, State of Pennsylvania, have invented certain new and useful Improvements in Safety Devices for Clothes Wringer, of which the following is a specification.

This invention relates to a certain new and useful improvement in power driven clothes wringer and more particular to a safety feeding device which enables the operator to feed the clothes to the press rolls without using the hand as is the ordinary custom.

In this practice with power driven rolls, the fingers oftentimes become caught between the rolls and are badly injured.

It is an object, therefore of this invention to provide a device of this character which is durable and simple in construction, inexpensive to manufacture, and can readily be mounted on wringers without any structural change.

So much only of the wringer frame and accompanying parts is illustrated as is deemed necessary to describe the improvements which are applied thereto.

In the accompanying drawing, forming a part of this specification and in which like numerals are applied to designate like parts throughout the same.

Fig. 1. Is a side elevation of the clothes wringer showing the application of my improved construction of feeding device.

Fig. 2. Is a section view taken on the plane of line X—X in Fig. 1, and shows feeding members in a closed position, which is, effective position.

Fig. 3. Is a section view taken along line Y—Y and shows the position of feeding bars when closed and gives a clear view of its construction.

Fig. 4. Is a section view taken along line Y—Y and shows the position of feeder bars when at rest or in an ineffective position.

In a more particular description of the parts, 1 designates the side frame member of the wringer. 2 designates the upper transverse member which unites the upright members. 3 designates lower transverse member which is also included in the frame structure. 4 and 5 designate the usual wringer rolls which are driven from their ends in a well known manner. 6 designates

guards at the ends of press rolls which are of a well known form.

Thus far, the elements referred to embody well known constructional part of power driven wringer.

My improved construction of feeding device comprises brackets 7 upon which are mounted feeding arm 9, one end being pivoted at 8, and are connected together by bar 11, each end of which, is pivoted at 10 to feed bars 9, connecting bar 11 being provided with means of adjustment 12. 13 designates spring for returning feeding bars to ineffective position as shown in Fig. 4. 14 designates part of bracket members 70 which rests upon wringer member 6, being obvious this gives a more rigid construction controlling outward and inward movements of members 9 as shown in Fig. 3 and Fig. 4. The feed members 9 are loosely connected at one end by pivots 8 and extend out in front of wringer in which position it is ineffective. From this position, arms may be swung inward to feed clothing between press-rolls.

By placing the hand on the handle of feed plates and swinging longitudinal edges of feed plates against the clothing and bringing clothing into contact with press-rolls, feeding plates will abut on upward extended 85 flange of bracket 7 and when released they will return to ineffective position, when again end of feeding member abuts on bracket 7.

When one member 9 is moved inward or outward, connecting bar 11 acts upon the other member 9 and causes it to function in like manner. The connecting bar being pivoted to swinging arms 9 by pivots 10. The connecting bar being provided with adjustment nut 12. This gives a finer adjustment in scope of movement between both members 9 and provides means for taking up all wear between these members.

To move feed members back to ineffective 100 position, a spring 13, is employed, one end of which is connected to member 11 and its opposite end to wringer frame.

The feed arms 9 have one free longitudinal edge to bring clothing in contact with 105 press-rolls. Their opposite edge, being curved downward, prevents clothing from catching and being injured.

From the foregoing description it will be seen that I have provided a feeding device 110

composed of a pair of brackets which can be detachably mounted on a wringer frame and having arms pivotally mounted at one end and swinging on the same plane as presser rolls, a connecting bar being pivoted to said arms and having means for adjustment, a spring attached to connecting bar and wringer frame.

Having described my invention what I claim as new and desire to secure by Letters Patent is:

1. The combination with a clothes wringer having end members and presser rolls journalled therein, of brackets mounted on said end members, a pair of feed arms pivotally mounted at one end to said brackets, and adapted to be freely swung towards the effective point of said rolls and an adjustable rod connecting the feed plates to cause them to function in unison.

2. The combination with a clothes wringer having end members and presser rolls journalled therein, of brackets mounted on said end members, a pair of elongated feed-
25 ing plates, one of which is pivoted to each of said brackets, and adapted to be freely swung toward the working portion of said rolls, and a connecting rod pivotally connecting said plates whereby movement of one plate toward operating position with respect to said rolls will effect a similar movement of the other plate.

3. An attachment for clothes wringers having presser rolls said attachment comprising a pair of brackets mounted on the frame of the wringer, a pair of feed plates mounted on said brackets and adapted to swing horizontally into position at the working edges of said rolls, an adjustable connecting bar connecting said plates, and a spring having one end fastened to the con-

necting bar and the other end fastened to the wringer frame to automatically move the plates to inoperative position.

4. The combination with a clothes wringer having presser rolls journalled on a frame, of a pair of brackets mounted on the frame, a pair of elongated feed plates pivotally mounted at one of their ends to said brackets, one longitudinal edge of said feed plates being rolled for preventing injury to the clothes being treated with the other longitudinal edge thereof arranged to engage the clothes and force them between the rolls, an adjustable rod connecting the feed plates to cause them to function in unison, and a spring, one end of which is connected to said rod and the other to the wringer frame to automatically move the plates to inoperative position.

5. A pair of feed arms pivotally mounted at one end to a wringer frame member, one of each of their edges being curved downward, their other free longitudinal edges being in a position to be swung inward toward the effective point of the press rolls.

6. An attachment for a clothes wringer having presser rolls, said attachment comprising a pair of brackets mounted on the frame of the wringer, a pair of feed arms pivotally mounted at one end to said brackets and a connecting bar pivotally mounted to said feed arms as means for swinging the arms in unison toward the effective point of said presser rolls, a spring, one end of which is connected to said rod and the other to the wringer frame, to automatically move the plates to inoperative position.

LESTER S. GUNDERMAN.
